LIQUID LEVEL INDICATOR FOR A STORAGE BIN

Clarence B. Coleman and Harry B. Kattelmann, Oakland,
Calif., assignors to Fabricated Metals, Inc.

Filed Aug. 19, 1970, Ser. No. 24,580

Term of patent 14 years

Int. Cl. D10—04

U.S. Cl. D52—6

FIG. 1

FIG. 2

FIG. 3

FIG. 1 is a top plan view of a liquid level indicator for a storage bin showing our new design;

FIG. 2 is a front elevational thereof; and

FIG. 3 is a perspective view thereof.

The broken line representation of a storage bin in FIGS. 1 through 3 is for purposes of illustration only.

We claim:

The ornamental design for a liquid level indicator for a storage bin, as shown and described.
